CLAIM

The ornamental design for a switch buckle of folding tents, as shown and described.

DESCRIPTION

1. Switch buckle of folding tents

1.1: Perspective

1.2: Perspective

1.3: Front

1.4: Back

1.5: Left

1.6: Right

1.7: Top

1.8: Bottom

1.9: The location of the switch buckle of folding tents

The broken lines shown in the figures are for the purpose of illustrating portions of the switch buckle of folding tents and form no part of the claimed design. The additional broken lines shown in FIG. 1.9 that show the wheels, base plates, and axle, illustrate environmental information and form no part of the claimed design.
